UNITED STATES PATENT OFFICE.

BENNETT C. SILVER, OF CHICAGO, ILLINOIS.

CHILD'S SWING-SEAT.

1,265,126.

Specification of Letters Patent. Patented May 7, 1918.

Application filed January 23, 1917. Serial No. 143,890.

To all whom it may concern:

Be it known that I, BENNETT C. SILVER, a citizen of the United States of America, residing at Chicago, in the county of Cook and 5 State of Illinois, have invented certain new and useful Improvements in Children's Swing-Seats, of which the following is a specification.

My invention relates to an improvement 10 in a child's swing-seat, and the objects of my invention are, first, to provide a construction of the class which will readily permit placing the child in and taking it from the seat and prevents the child's fall or escape 15 in the absence of an attendant; second, to afford a seat which may quickly be removed from the frame giving it shape to be laundered; and, third, the provision of means having one free end and suitable to 20 be attached to and detached from the body of the seat to restrain the child's body from slipping out of the seat.

With the foregoing and other objects in view, my invention consists in the novel features and in the novel combination and arrangement of parts hereinafter fully described, illustrated in the accompanying drawings forming a part of this specification, and particularly pointed out in the 30 claims hereunto appended.

Figure 1 of the drawings is a perspective of the invention with the restraining flap unhooked,

Fig. 2 is a similar view with flap hooked, 35 Fig. 3 is a section on line 3—3 on Fig. 2,

Fig. 4 is a perspective view of a modified form in the construction of the seat.

Similar numerals refer to similar parts throughout the several views.

40 The seat or basket A is made up preferably of a suitable textile fabric composed of a single strip forming the sides and bottom 5, a rear portion 6, a narrow front strip 7, each having an upper hem 8, attached to the rigid frame 9, preferably of metal and rectangular in shape. The rear portion 6 is sewed laterally at 10 to the strip 5, as indicated in dotted lines in Fig. 1.

45 The restraining flap 11 is sewed at one end to the strip 5 as indicated by dotted line 12 and carries hooks 13 at one end for engagement with eyes 14 on the strip 7.

Straps 15 of any desired length afford suitable means whereby to hang the seat 55 sufficiently above the floor or the ground

from the ceiling or from a tree in a well known manner.

The relatively narrow flap 11 secured at the opened end of the seat leaves a comparatively large opening 16 to facilitate seating 60 in and removing the child from the basket-like seat A.

The strip 7 is sewed or otherwise secured at its ends to the side portions 5.

In Fig. 4 is disclosed a slightly modified 65 form having parallel rows of holes with eye-lets 17, 18, therein and when the upper edges of the fabric seat are folded over the rigid frame 9, the rows of eye-lets register to enable the threading of a tape 19 there- 70 through and tying the same as at 20 to provide simple means for detaching the seat from its rigid frame when the seat is to be laundered.

The flap 11 when fastened at its free end 75 to the basket spans the opening 16 in the side of the basket.

The straps 15 preferably are woven and the upper ends thereof are secured to a metal ring for engagement with an elevated point 80 for suspending the basket sufficiently above the floor or ground to permit the child's feet to touch the floor and thus give the basket swinging movement for its own entertainment.

Owing to the simple character of the invention, on reference to the drawings taken together with the above description, the construction and its mode of operation, it is 85 thought will be readily understood.

It will be understood that changes, variations, and modifications in the details of the invention within the scope of the claims may be resorted to without departing from the spirit or sacrificing any of the advantages 95 thereof, hence I do not limit my invention to the exact construction and arrangement of parts shown and described.

Having thus fully described my invention, what I claim as new, and desire to secure by Letters-Patent, is:

1. In a child's swing-seat, the combination with a rigid frame and suspending means therefor, of a textile seat the upper edges of which are provided with parallel 105 rows of eyelets and folded over the rigid frame and means threaded through the eyelets for attaching and detaching the seat from the rigid frame.

2. In a child's swing-seat, the combination 110

with a rigid frame and suspending means therefor, of a textile seat the upper edges of which are folded over the rigid frame and having an opened end with a restraining flap secured at said open end and means for fastening the free end of the flap to the body of the textile seat.

3. In a child's swing-seat, the combination with a rigid frame and suspending means therefor, of a textile seat the upper edges of which are provided with parallel

rows of eyelets and folded over the rigid frame and having an open end with a restraining flap secured to the said seat at one end and means for fastening the free end of the flap to the body of the textile seat. 15

In testimony whereof I affix my signature in the presence of a witness.

BENNETT C. SILVER.

Witness:

SCOTT M. HOGAN.
